KEY BLANK

Application filed January 8, 1930. Serial No. 419,277.

Keys for locks, in the nature of their use, are necessarily highly diversified. Not only do the keys of different manufacturers vary widely in their patterns but an equally wide variance of the keys of each manufacturer must be provided. To enable the user to obtain a duplicate conveniently has always presented a problem which can hardly be said to have been solved satisfactorily up to the present time. One method employed is to use the key which is to be duplicated as a pattern for filing down a proper blank by hand. This method, of course, requires possession of the key which is to be duplicated and some little skill on the part of the locksmith. Another method is for each manufacturer to number its keys and place in the hands of those having suitable equipment a code which reveals the blank and pattern of the key with reference to its particular number. With such data and a machine a duplicate key can be made. The duplicating machine employed for preparing a key having a particular pattern as revealed by the code book is expensive and its general use thereby restricted. The result is that today it cannot be said that the user of a key has at his command a widespread and convenient service for obtaining a duplicate. With the recent widely increased use of locks on automobiles, for instance, this inconvenience is a condition that has come home to the public. With increasing demands for service by the public the manufacturers of automobiles have become sensitive to the practical difficulties of meeting this demand for service in the duplication of keys for the locks on the cars which they sell.

The principal object of the present invention is to provide a method which shall be simple and inexpensive for the making of keys in accordance with a known pattern. By this method it is sought to make it possible for keys to be quickly duplicated without the use of special equipment or tools, by unskilled workers. By such a provision it becomes possible to establish a wide-spread service through all ordinary agencies for the duplication of keys. For instance, pursuant to the improved provision it becomes pos-

sible for all sales representatives of all makes of automobiles to carry in stock a relatively small number of inexpensive key blanks corresponding to the keys in use on the locks of the make of automobile which they handle and to duplicate keys from such blanks upon demand of their customers by a few minutes' unskilled effort on the part of an ordinary shop mechanic using a standard tool. A further object of the invention is to provide a key blank which may be readily marked during the course of its manufacture with such indicia as may be necessary to enable the improved method to be practiced in cutting a key therefrom. A further object of the invention is to provide such indicia on a key blank as will enable any one of a variety of keys to be cut from the blank the indicia itself being of such a character as to indicate clearly to the workman (having reference to the code) what operations are to be performed to give the desired completed pattern.

While it will be understood by one skilled in the art that key blanks differ in cross sectional form and that keys differ in pattern according to the number of tumblers controlled by the particular key and that the relative dimensional spacing and depths of notches or slots in the patterns of keys may vary, all such differences are recognized and coded in accordance with the present day practice. This being true it will be understood as the description proceeds herein that the invention is applicable to any key blank although being illustrated in connection with blanks in which the cross sectional form and dimensional relationships of the pattern are assumed by way of illustration.

The improved key blank in accordance with the invention will be provided with a series of lines which will indicate the depths of the various notches or slots used by the particular manufacturer in that type of key. It will be provided with indicia indicating the dimensional spacing of the notches and slots of that particular type of key and in the number to which such key is formed with notches and slots depending on the number of tumblers which the key is adapted for control of.

The invention will be described in greater detail with reference to the key blanks illustrated in the accompanying drawings, in which:

5 Figure 1 is a view in side elevation showing a key blank formed with the improved indicia to indicate the various depths of notches to be cut therein.

10 Figure 2 is a view looking down on the top edge of the blank shown in Figure 1 and showing indicia on the edge to indicate the spacing of the apices of the notches to be cut therein.

15 Figure 3 is a view in cross section on an enlarged scale taken on the plane indicated by the line 3-3 of Figure 1 and looking in the direction of the arrows, the indicia being exaggerated as consisting in grooves milled or etched in the blank.

20 Figure 4 is a view in side elevation of a key blank of a somewhat different type having ungrooved sides and in which rectangular slots are cut in the edge to constitute the pattern.

25 The key blank α shown in Figures 1, 2 and 3 may be grooved or ribbed along one or both of its side faces as indicated in Figure 3, the invention not being concerned with the cross sectional form of the blank but being 30 applicable to blanks of varying forms. A key formed from such a blank usually has along its top edge α' a series of notches. Such notches are of a predetermined number depending on the number of tumblers 35 in the lock for which the key is made. Further, these notches have their apices spaced apart a predetermined distance and each notch measured from the edge α' is of a predetermined depth. In the code book now

40 furnished to locksmiths there will be set forth, for example, under a particular key number which every key bears, the corresponding blank which is to be used for duplicating such key. Such a blank, of course, 45 has a cross sectional form corresponding to the key whose number is being considered. The code book will, in addition, state the number of notches along the upper edge, the distance of their apices apart, and the depth 50 of each notch. Under the present day practice this data is used for setting a special key cutting machine so that it will cut the desired number of notches in the specified dimensional relationship and to the specified 55 depths. Such a machine is expensive and its use comparatively limited for that reason.

In accordance with the present invention the key blank α when manufactured has formed on one face a series of parallel lines α^2 , α^3 , α^4 , 60 which may be milled, etched or otherwise formed as may be found most desirable. The line α^2 is spaced a predetermined distance from the upper edge α' depending on the standardized depth of such notches as the 65 particular manufacturer may employ in the

particular key under consideration. The next line α^3 is similarly spaced from the upper edge α' a predetermined distance depending on the next greater depth of notch that may be required in the particular key. 70

Similarly, the third line α^4 is spaced from the upper edge α' such a distance as will indicate the depth to which the third deepest notch may be required. While it is frequently true

that the depths of the various notches are 75 multiples of the shallowest notch this is not

always true and is not a condition which is important in the present invention because

as indicated above the determining factor in 80 each instance is the depth to which each notch is to be cut considering the top edge α' as the base line. Having this in mind it will be evident that the three lines α^2 , α^3 and α^4 and any additional number of lines, where

required, shall represent the notch depths. 85 The blank α is also provided in accordance with the invention with suitable indicia to indicate the distance between the apices of the various notches which are to be cut. It

is immaterial what form such indicia shall 90 take and where it shall appear on the surface of the key blank. In Figures 1 and 2 trans-

verse lines α^5 , α^6 , α^7 , α^8 , α^9 , α^{10} are shown as 95 provided on the top edge α' and these lines are also shown as extended down the side face

of the blank to intersect the longitudinally extending parallel lines α^2 , α^3 , α^4 . It may be 100 found equally convenient to omit the lines α^5 , α^6 , etc. from the top edge or from the side face and to place them on the reverse face and the invention is not to be limited as

to such details. The purpose of these lines is to indicate for the particular key blank 105 the distance between the apices of the several notches to be cut in its top edge.

With the blank formed in the manner de- 110 scribed and preferably during its stage of manufacture it is ready for use, to be made when required, as a duplicate for any one of a great variety of keys having different pat-

terns. When the number of the key to be 115 duplicated is known it is necessary only then to ascertain from the code book the depths of the notches. These depths are given in the code book in their order from one end of the key to the other.

The method employed in making the de- 120 sired key having the improved blank in stock is as follows: A convenient tool, preferably a file, is employed to cut in the notches in

succession along the top edge α' . The work- 125 man has determined from the code book that the first notch viewed at the end of the key blank as shown in Figure 1 is to be two units in depth. He starts to file on the indicat-

ing line α^{10} knowing that on that line is to be the apex of the notch. He files until he has reached the second line α^9 as viewed from the side of the key blank and when he reaches

that line he will know that the notch is two 130

units in depth. He continues to file until he reaches the third line α^8 as viewed from the side of the key blank and when he reaches

that line he will know that the notch is two 135

units in depth. He continues to file until he reaches the fourth line α^7 as viewed from the side of the key blank and when he reaches

units in depth conforming to the code book and its apex is properly placed. He will determine from the code book that the second notch which is to have its apex on the line a^9 is to be filed one unit in depth terminating at the first indicating line a^2 . From the code book he will find that the third and fourth notches are each to be two units in depth and he files them in on their space lines a^3 , a^7 , respectively, until their apices fall on the depth line a^8 . The code book will tell him for the particular key that the fifth notch, which is to be cut at the line a^6 , is one unit in depth and he will stop filing when this notch has reached the first line a^2 . The sixth notch cut on the line a^5 is shown to have a depth of three units and so will extend down to the guide line a^4 . When his filing is thus completed, using the indicia as described, an accurate and correct duplicate of the particular key by number will be completed.

Figure 4 shows a somewhat different type of key blank and is included merely to emphasize that the invention is not limited in its use to any particular type since the principle may be incorporated in any blank. In this figure the blank b has no grooves or ribs on its side faces and is intended for use in a lock where rectangular slots along the bottom edge b' are required in accordance with a predetermined pattern. This blank will be manufactured with a plurality of parallel guide lines b^2 , b^3 , b^4 on one face spaced predetermined distances from the edge b' . Similarly, a series of guide lines b^5 , b^6 , b^7 , b^8 , b^9 , b^{10} , b^{11} , b^{12} , may be provided on the side face intersecting the first named guide lines or, as pointed out hereinbefore, these last named lines may appear only along the edge 40 of the blank or on the opposite face. From the code book, to make a particular key, having the proper blank b , slots of standard form will be filed in at intervals as indicated by the code book each slot being of a depth 45 directed by the code book. It will be noted that the edge of the blank is not indented opposite the guide lines b^9 , b^{10} , but this is a condition that will be indicated by the code book since the edge b' can be regarded relatively as the base line and the bottom of a slot of least depth, all of the other slots being related thereto in depth as indicated by the other guide lines b^2 , b^3 , b^4 .

The improved key blank and method of 55 making keys therefrom lend themselves to the widest use. Having the blanks in stock it becomes possible for anyone with code directions as to the depths of the successive notches to make a key without any skill 60 merely following the indicia as directed. The resulting pattern of the key is necessarily that desired. No special equipment is needed, no skill is required, the capital investment is only that of such key blanks for 65 keys as may need to be duplicated and the

time to effect the duplication is a minimum. The resulting condition makes it wholly practical to place within the reach of every key user a simple, convenient and inexpensive service in proximity to his home. In fact, in its most beneficial aspect it makes it possible for stores to sell such blanks with code books thereby enabling the user of the key to make his own duplicate.

While the method of cutting the notches 75 as described refers to their cutting in succession beginning from the end of the key blank, one skilled in the art will understand that it may be better practice to cut all of the shallowest notches first and proceed then to the 80 cutting of the next deeper notches and so on.

Another point to understand in connection with the invention is that it is not limited to the application of the indicia to the key blank 85 during its manufacture since such indicia can be applied by hand at any time through the use of any suitable tool or device.

The further point that will be understood by one skilled in the art is that the top edge a' of the key blank as described is not necessarily 90 the number 1 cut or base line according to the code but this fact makes no difference in the understanding of the invention since if it is not the base line all of the other notches required by the code for a particular key will 95 have the depth indicated in the code.

It will be evident that the blanks may be provided with indicia which show only the spacing of the notches or only the depth of the notches or both since the provision of indicia for either spacing or depth would have considerable practical value commercially in the making of keys from blanks.

It is intended by the appended claims to cover the principle underlying this invention in its broadest application and it is to be understood that where this principle is embodied by the means set forth herein enabling keys to be made in accordance with the improved method no limitations are to be imposed as to the character of the key blanks nor on the means employed for generating indicia.

What I claim is:

1. A key blank provided with indicia in predetermined dimensional relationship as to depth to be followed in cutting according to code. 115
2. A key blank provided on its face with parallel lines spaced apart at predetermined intervals as to depth to be followed in cutting according to code. 120
3. A key blank provided with indicia in predetermined dimensional relationship as to location and depth to be followed in cutting according to code. 125
4. A key blank provided on its face with parallel lines spaced apart at predetermined intervals as to depth to be followed in cutting according to code and other lines at prede- 130

terminated spaced intervals to be followed as to location in said cutting.

5. A key blank provided on its face with parallel lines spaced apart at predetermined intervals from one edge of the blank to be followed as to depth in cutting according to code and transverse lines along the said edge of the blank at predetermined spaced intervals to be followed as to location in said cutting.

10 This specification signed this 2d day of January A. D. 1930.

REUBEN SIMON.
